NECK PROTECTOR FOR USE WITH HAIRDRESSER'S WRAPPERS OR THE LIKE

Arthur Förster, Gorlitz, Germany

Application August 9, 1934, Serial No. 739,095
In Germany September 1, 1933

1 Claim. (Cl. 2—50)

This invention has reference to neck protectors for use with hairdressers' wrappers or the like themselves used to protect the dress during hair-cutting, shampooing, hairdressing, shaving and such like.

It rarely happens that a hairdresser provides each customer with a fresh wrapper or the like and in order to give an appearance of cleanliness it is usual for the hairdresser to insert a strip 10 of thin paper between the neck of the customer and the wrapper or the like which is gathered round the neck. From the point of view of hygiene it is seldom that anything is gained by this since the wrapper or the like is generally arranged round the neck of the customer before the strip of paper is placed in position. Moreover, the strip of paper does not effectively prevent falling hair from getting between it and the customer's neck.

20 Various proposals have been made to provide an efficient neck protector. There has, for example, already been proposed a neck protector consisting of a strip of crepe paper having sewn along one longitudinal edge a band of cotton 25 fabric adapted when the ring is placed round the neck to form a collar, the other longitudinal edge of the strip being expanded fan-wise and the ends of the strip being secured together by means of a press-button. This and others of the prior 30 proposals referred to are too complicated and also too expensive with the result that it and their use in practice has not become general.

The object of the present invention is to provide a neck protector for use with hairdressers' 35 wrappers or the like during haircutting, hairdressing, shampooing, shaving etc., which while affording a perfectly hygienic protection to the neck will be sufficiently inexpensive to enable a hairdresser not only to incur the additional cost 40 entailed by its use but to also effect a considerable saving in comparison with the cost of protectors hitherto proposed.

A neck protector in accordance with the invention consists of a strip of crepe paper of such 45 a length that it requires to be pulled out to a considerable extent (e. g. approximately twice its original length) to be fitted in position and having its ends adapted to be secured together. The elasticity of the strip of crepe paper enables the 50 protector to fit snugly round the neck and the cost of the crepe paper is so little more than that of the tissue paper hitherto sometimes used that there is no inducement for a hairdresser 55 to use the crepe paper protector more than once, the more so as the fact of a protector being pulled out would at once reveal to a customer that it had been previously used. In order, however, to make it impossible to use the improved protector

more than once, its ends are adapted to be secured together in such a manner that the protector must be torn through in order to remove it. Conveniently, the ends of the protector may be adapted to be secured together by means of 5 an adhesive or a non-releasable press-button or like fastening.

In the accompanying drawing Fig. 1 is a plan of a neck protector in accordance with the invention laid out flat, Fig. 2 is a fragmentary elevation showing the ends of the protector sealed together in such a way as to necessitate tearing of the protector in order to remove it, and Fig. 3 illustrates the protector in use.

Referring to the drawing, the improved protector comprises a strip *a* of crepe paper which may suitably be about 20 c. m. long and about 7 c. m. wide, and which is capable of being drawn out to about twice its normal length when it is to be fitted in use. The ends of the strip *a* have applied to them coatings *b* of adhesive for securing them together. The coatings of adhesive are provided on the inner face of the strip so that upon the ends being turned or bent outwards and moistened the ends are secured by simply pressing them together as shown in Fig. 2, and the strip *a* must be torn through in order to remove it.

Instead of employing an adhesive the ends of the strip *a* may be provided with the members *c* 30 of a press-button of the non-releasable kind the members *c* having their co-operative faces on the inner side of the strip *a* so that the ends can be secured by turning them outwards and pressing them together.

It will be apparent that the invention provides a neck protector which is efficient in use, is inexpensive in cost and cannot be used a second time.

Having now particularly described and ascertained the nature of my said invention, and in what manner the same is to be performed, I declare that what I claim is:

A neck protector for use with hair dressers' wrappers and the like, said protector comprising 45 an elongated strip of crepe paper, said protector being stretchable in its longitudinal direction substantially throughout its entire width and prior to use being substantially shorter than the circumference of the neck of the wearer, said protector being adapted to be stretched to the full circumference of the neck of the wearer when in use, and an adhesive situated at both ends of said strip of crepe paper, whereby said ends may be permanently joined while the strip surrounds 50 the neck of the wearer, so that the strip must be torn in order to remove it after use.

ARTHUR FÖRSTER.
